J. Q. SHERMAN

FLAT BED MANIFOLDING MACHINE

Filed April 19, 1921

BY

John Q. Sherman

Albert H. Bell
ATTORNEYS.

UNITED STATES PATENT OFFICE.

JOHN Q. SHERMAN, OF DAYTON, OHIO.

FLAT-BED MANIFOLDING MACHINE.

Application filed April 19, 1921. Serial No. 462,677.

To all whom it may concern:

Be it known that I, JOHN Q. SHERMAN, a citizen of the United States, and a resident of the city of Dayton, in the county of Montgomery and State of Ohio, have invented certain new and useful Improvements in Flat-Bed Manifolding Machines, of which the following is a full, clear, and exact description, reference being had to the accompanying drawings, forming part of this specification.

My invention relates to manifolding machines particularly those employing a typewriter for making impressions on the sheets of paper used, and those employing a flat bed on which the writing is done.

It is the object of my invention to provide a pin wheel feed for paper, in such a device, and particularly to drive said pin wheel device by a motor, said feed being coupled up with a device for withdrawing the webs of paper from a storage cabinet at the same time.

In connection with the withdrawing device, I provide as part of my invention, a movable feeding and aligning device for the webs of paper, which may be individual for each web, but in any case is so synchronized as to the amount fed that ample will be present at all times, for the main feed, and all webs aligned both longitudinally and transversely so that all the main feed needs to do is to correct mis-alignment arising between the withdrawing device and the said main feed.

The movement of the feeding device is to permit of ready alignment of the various webs with relation to each other, and then moving them in a body to a position substantially parallel with the flat bed, so that no webs have more strain on them than the others.

I accomplish my object and other advantages to be noted, by that certain construction and arrangement of parts to be herein-after more specifically pointed out and claimed.

In the drawings,

Figure 1 is a side elevation of a device made according to my invention.

Figure 2 is a detail elevation, at right angles to Figure 1, showing the carbon paper feed, with its change speed mechanism.

Figure 3 is a detail side elevation of one of the carbon paper feed spindles.

In a co-pending application, Serial No. 370,839, filed in my name and that of Albert W. Metzner, there is described an electric operating device for driving a sprocket or pin wheel feed for manifolding register paper, having marginal holes therein. In the present application, the motor drive is the same as in that of the said application for patent, and the novelty residing in the use of said device herein resides only in its combination with other features not present in said earlier application.

The pin wheel feeding device for the main feed is substantially that of the patent to Schirmer, No. 940,481 to which reference is hereby made.

The interleaving device, which is employed for the individualizing of the various webs of paper, and preventing fracture of the edges of the interleaved carbon paper is that of the Sherman and Metzner application Serial No. 391,499 and reference is hereby made to said application for the details of this structure.

Referring to the machine in general, the writing bed or platen is indicated at 1, and frame at 2, and the storage cabinet at 3. The typewriter 4 moves over the platen in the usual manner, and the paper webs 5 are mounted in the storage cabinet in rolls 6, from which they may be withdrawn without excessive friction or hold back.

In a channel or groove 7 in the storage frame are set the series of bars 8, which carry the carbon paper protecting sheets or strips 9, each strip being of double structure so as to overlie the edges of the various webs of carbon paper 10, and protect them from fracture due to the movement of the webs of paper therebetween.

Mounted on shafts 11 on the upper portion of the storage cabinet 3, are a series of pin wheels 13, of like nature. Pivoted at 14 to the frame of the storage cabinet is a frame made up of side bars 12 suitably

braced together and in this frame is mounted a series of idler rollers 14^a, one roller between each pair of pin wheels to guide and hold the paper on the pin wheels.

5 As shown, each one of the shafts 11 has a sprocket 15, and a chain 16 inter-connects all sprockets, and thus all shafts, and holds them in a fixed mutual relation.

The frame has two positions, one (Figure 10 1) elevated at an angle to the horizontal, where it is held by a bell crank latch 17 engaging over a lug or catch 18 on the storage frame and the other lowered to a horizontal position with the lug 19 resting on the stop 15 20 on the storage frame.

The latches and stops may be duplicated or but a single set employed.

In loading the machine, the frame is let down to its horizontal position and the webs 20 of paper drawn from the rolls, and set over the pin in such a way that the proper point on each web has its apertures set over the proper pin of each pin wheel. This can be readily determined by observation, and as 25 in all types of pin wheel feed machine, the holes will normally be arranged uniformly along one or both margins of the webs.

After the webs are arranged over the balance of the machine the operator raises the 30 frame to its elevated position, so as to bring the idler rollers into proper position to guide and hold the respective webs of paper on their respective wheels. In driving the pin wheels, the revolution of any one of the set 35 will impart revolution to the others through the sprockets and chain above noted.

I do not desire to be limited to the use of an individual pin wheel for each web, as experience has shown that several webs may 40 be fed by means of a single pin wheel. I will ordinarily employ two pin wheels for each shaft, but this also is optional, as a single pin wheel for each web or webs will suffice.

45 As noted above, the carbon paper protecting device as more particularly described in another application, is arranged vertically and the webs pass from it to the platen of the machine.

50 At the issuing end of the platen, there is mounted a main feed shaft 30, on which are mounted one or more pin wheels 31, and suitable pressure roll lifting cams, for which see the Schirmer patent above referred to. The pressure roll, varying from the Schirmer 55 patent, is shown at 32, and is mounted on a pair of arms 33, set fixedly on a shaft 34. This is under the influence of a spring 35, which acts to keep the roll in place on the 60 cams above noted.

On this feed shaft 30 is also a sprocket 36, from which a chain 37 runs to an idler sprocket 38 on the side of the machine. This sprocket carries another sprocket 39, which 65 is connected by a chain 40 with the sprocket

41 on the first of the shafts in the frame over the paper storage cabinet.

Thus when the main pin wheel feed is operated, the storage feed is operated also, and as is evident, the relative arrangement 70 of sprockets will cause the withdrawing pin wheels to operate at a speed to feed the same amount of paper as the main pin wheels will feed.

As each succeeding pin wheel is set further 75 back from the main feed in loading the device the proper apertures must be selected to provide alignment for all copies at the main feed, while at the same time providing the same looseness for each web between the 80 two feeding points.

I have thus provided this storage unwinding feed to operate as a unit with the main feed in order to obtain a sufficient looseness 85 of the paper webs between the two feeds in order to obviate the heavy pull or drag which would result if the main feed had to do all the work. In this way the main feed can function more properly in feeding the forms across the platen and in maintaining alignment at this point.

The machine shown has a motor operation, for which I have referred above to a pending application for the details. There is here shown a motor 42 of the type which 95 will automatically switch itself off upon extra heavy load being applied to it. This motor has a starting button 43 and a gear 44, which meshes with another gear on the feed shaft. A suitable stop located on the main feed shaft comes in contact with a latch 45 at the end of each rotation of the shaft and this will also cause the motor to stop. When it is desired to start the feed, the latch is 100 released and the starting button pressed.

105 Other details of the motor drive I have not described, as they are amply taken up in the said application.

The carbon paper feeding devices in this 110 invention are of special type, so as to permit of an adjustable feed of paper, and also a feed which varies between the uppermost and lowermost of the strips of paper used. This carbon paper device, Figures 2 and 3, is on the opposite side of the machine from that shown in Figure 1 and it will be understood that on the side shown, the carbon paper is mounted on a pair of ordinary rolls 50, and thence drawn up and across the platen, being there interleaved between the webs of paper 115 to be written upon.

I prefer to employ, say two rolls of the paper, one having more strips than the other, and the one having the fewer strips set so as to have its strips come uppermost on the 120 platen, and thus receive the greatest amount of wear. As will be noted, these sheets are renewed more rapidly than those below them.

125 On the other side of the machine from that

shown in Figure 1, the feed shaft is extended as at 51, and supplied at its outer end with a support in the side of the carbon paper trough 52. The carbon trough is also provided with a rigid plate 53, having a series of holes 54 therein.

Engaging over the shaft extension 51, is a sleeve 56 which sleeve carries a fixed handle 57 thereon, said handle having a pin 10 at its end which slides under spring tension as at 58, to engage in one of the series of holes 54. The sleeve also carries a pinion 59 thereon and the handle carries a pinion 60 which meshes with the pinion 59 and is 15 planetary thereto. The pinion 59, while carried by the sleeve has a key disk 61 on its outer end for engaging in the key-way 62 in the shaft portion 51.

This construction enables the operator to 20 shift the pinion 59 along the shaft, and hold it in a number of positions and keep the pinion 60 in mesh therewith at all positions. The handle does not turn with the shaft, but 25 the pinion 59 does and will drive the small pinion 60.

There are two carbon paper spindles, in this instance, as shown at 63 and 64, both of which will have cores 65 set thereover, with the cores having starting clamps or 30 rods 66 of familiar construction and operation.

On the spindle mounting stud 63^a, set in the bracket 63^b is a loose worm gear 67, and on the spindle mounting stud 64^a, also mounted in said bracket is a loose worm gear 68 of larger size than the gear 67. A shaft 67^a mounted to revolve in the sides of the trough is shown as extended across both of the worm gears and carries worms 69 and 70, 40 which mesh with the two worms, and drives one faster than the other, as will be evident.

The worm gears are loose on the spindle mounting studs, and carry pins 71, which 45 enter holes 72 in the ends of the cores on the spindles so that the cores and spindles may be withdrawn without disturbing the action of the worms.

The shaft 67^a has mounted fixedly thereon, 50 a set of gears 73 to form a cone gear, which will provide different speeds of drive by the positioning of the pinion mechanism on the feed shaft extension 51. A handle 74 may be used for revolving the shaft 67^a, for starting carbon paper on the spindles, at which 55 operation the shiftable gear device on the shaft portion 51 will be moved entirely out of meshing position with the gears at 73.

By this construction now described, it is 60 evident, when the strips of carbon paper are brought over the platen, and secured to the spindle cores 65, that the operation of the feed will draw a small portion of the carbon paper over the platen at each feeding operation. The lowermost sheets will be drawn 65

more slowly than the uppermost ones, and the speed of both types may be varied.

One of the chief items of upkeep of large manifolding machines of this character is carbon paper, since heavy blows must be struck to make six or more impressions, and this will deteriorate the carbon paper rapidly. Also the carbon paper will stick to the paper written upon and cause the feed to operate improperly, so that some small 70 amount must be fed at each operation to break up adhesions.

Grades of carbon paper vary quite widely, and the operator would not require such a frequent renewal for good paper as for bad, 80 and will always require a more rapid renewal of upper sheets than lower sheets.

My mechanism takes care of all of these features and makes the machine much more economical of carbon paper than one which 85 makes no such provision.

I do not desire my failure to mention equivalent structures in the above description, to be construed as a limitation of the claims that follow, as I have merely shown and 90 described a structure which is preferred by me for most accurate operation and permanence of repair.

Having thus described my invention, what I claim as new and desire to secure by Letters Patent, is:—

1. In a device of the character described, the combination with a flat platen, a pin wheel feed for drawing webs of paper over said platen, a storage element, pin wheel devices for withdrawing the webs of paper from said storage element, to supply them to the platen, said devices adapted to feed each web an equal distance at each operation, and means for driving the pin wheel feed 100 and pin wheel devices synchronously, from a common source.

2. In a device of the character described, the combination with a flat platen, a pin wheel feed for drawing webs of paper over 110 said platen, a storage element, individual pin wheel devices for each web for withdrawing the webs of paper from said storage element, to supply them to the platen, means for driving the pin wheel feed and 115 pin wheel devices synchronously from a common source, and means for guiding and holding the paper webs on the pin wheel devices.

3. In a device of the character described, the combination with a flat platen, a pin wheel feed for drawing webs of paper over 120 said platen, a storage element, pin wheel devices for withdrawing the webs of paper from said storage element to supply them to the platen, means for driving the pin wheel feed and pin wheel devices synchronously from a common source, and means for guiding and holding the paper webs on the pin wheel devices, said means comprising a frame 125 130

with a series of rollers mounted therein, said frame having a pivotal mounting and means for retaining it in horizontal and inclined positions, for the purpose described.

5. 4. In a device of the character described, the combination with a flat platen, a pin wheel feed for drawing webs of paper over said platen, a storage element for paper, an individualizing device adapted to separate 10 each web of paper before it reaches the platen, and individual pin wheel devices for each web for withdrawing the webs of paper from the storage device before reaching the individualizing device, and means for driving 15 the pin wheel feed and pin wheel devices synchronously from a common source.

5. In a device of the character described, the combination with a flat platen, a pin wheel feed for drawing webs of paper over 20 said platen, a storage element for paper, an individualizing device adapted to separate each web of paper before it reaches the platen, a pin wheel device for withdrawing the webs of paper from the storage device 25 before reaching the individualizing device, comprising a series of pin wheels, and means for driving the pin wheel feed and pin wheel devices synchronously from a common source, a frame with rollers in alternate series with the pin wheels, and means 30 for retaining the frame at varying positions to facilitate mounting the webs over the pin wheel and to render substantially horizontal the path of the paper from the pin wheels 35 to the individualizing device.

6. In a device of the character described, the combination with a flat platen, a pin wheel feed for drawing webs of paper over said platen, a storage element, pin wheel devices for withdrawing the webs of paper from said storage element to supply them to the platen, and means for driving the pin wheel feed and pin wheel devices synchronously from a common source, said pin wheel 40 devices comprising a series of pin wheels, one pin or set of pin wheels for each web of paper.

7. In a device of the character described, the combination with a flat platen, a pin wheel feed for drawing webs of paper over said platen, a storage element, pin wheel devices for withdrawing the webs of paper from said storage element to supply them to the platen comprising a series of pin 55 wheels and means for driving the pin wheel feed and pin wheel devices synchronously from a common source, a frame with rollers in alternate series with the pin wheels, and means for moving the said frame to positions to facilitate mounting of the paper over the pin wheels and to provide a substantially horizontal path of the paper to the platen.

8. In a device of the character described, 60 the combination with a flat platen, an align-

ing and feeding device for drawing webs of paper over said platen, a storage element, an aligning and feeding device for withdrawing each of the webs of paper individually from said storage element to supply them to 70 the platen, and means for driving the aligning and feeding devices synchronously from a common source.

9. In a device of the character described, the combination with a flat platen, an aligning and feeding device for drawing webs of paper over said platen, a storage element, an aligning and feeding device for withdrawing each of the webs of paper individually from said storage element to supply them to 75 the platen, and means for driving the aligning and feeding devices synchronously from a common source, said means comprising in part a motor, with means for automatically stopping the feed action thereof for individual operations.

10. In a device of the character described, means for mounting carbon paper over the platen thereof, a feed device, driven spindle elements for feeding the carbon paper over 90 the platen, and connection from the feed device to the driven spindles for revolving them during feeding operations.

11. In a device of the character described, means for mounting carbon paper over the 95 platen thereof, a feed device, driven spindle elements for feeding the carbon paper over the platen, and connection from the feed device to the driven spindles for revolving them during feeding operations, said connections including a change speed mechanism.

12. In a device of the character described, the combination with a plurality of driven spindles for feeding carbon paper over a 105 platen, of a feed device for webs of paper over the platen, and connections from the feed device to the spindles, said connections having different speeds, whereby some of the spindles are driven more rapidly than 110 others.

13. In a device of the character described, the combination with a plurality of driven spindles for feeding carbon paper over a 115 platen, of a feed device for webs of paper over the platen, and connections from the feed device to the spindles, said connections having different speeds, whereby some of the spindles are driven more rapidly than others, said connections comprising also a 120 change speed mechanism common to all spindle feeds.

14. In a device of the character described, the combination with a feed device, of a carbon paper spindle feed shaft, driving connection thereto from the feed device, a plurality of carbon paper spindles, worm wheels for revolving the carbon paper spindles, and worms on the spindle feed shaft, said worm wheels and gears being arranged for differ- 125 130

ent speeds to different spindles, for the purpose described.

15. In a device of the character described, the combination with a feed device, of a carbon paper spindle feed shaft, driving connection thereto from the feed device, a plurality of carbon paper spindles, worm wheels for revolving the carbon paper spindles, and worms on the spindle feed shaft, said worm 10 wheels and gears being arranged for different speeds to different spindles, and the driving connection between the feed device and the spindle feed shaft comprising a change speed gear element.
- 15 16. In a device of the character described, the combination with a feed device, of a carbon paper spindle feed shaft, driving connection thereto from the feed device, a plurality of carbon paper spindles, worm 20 wheels for revolving the carbon paper spindles, and worms on the spindle feed shaft, said worm wheels and gears being arranged for different speeds to different spindles, and the worm wheels having detachable connection with the carbon paper spindles.
- 25 17. In a device of the character described, the combination of a flat platen, means for feeding a plurality of webs of paper over

said platen, a storage element for said paper webs and additional means for feeding the 30 paper webs from the storage element and to the platen to furnish strips for alignment and delivery over the platen, said additional means operating with the main feed to feed sections of each web of the same length per 35 operation as the feed is per operation of the main feed and comprising rotary means having interspaced teeth to engage interspaced holes in the paper webs.

18. In a device of the character described, 40 the combination with a typewriter and a flat platen for receiving the typewriter impression, of means for feeding a plurality of webs of paper in alignment over said platen, a storage compartment within which the 45 webs of paper are mounted in rolls and toothed rotary means for feeding the webs from the rolls to the platen, so as to maintain alignment thereof lengthwise and transversely and synchronously with the main 50 feed, to provide loose aligned strips for the typewriter and for delivery therefrom, said rotary means having interspaced teeth to engage interspaced holes in the paper webs.

JOHN Q. SHERMAN.
